UNITED STATES PATENT OFFICE.

WILL DEAN ALLEN, OF NEW DURHAM, NEW HAMPSHIRE, ASSIGNOR TO THE FULLER
BRUSH COMPANY, OF HARTFORD, CONNECTICUT, A CORPORATION OF CONNECTICUT.

DESIGN FOR A HANDLE FOR BRUSHES OR SIMILAR IMPLEMENTS.

Application filed July 14, 1924. Serial No. 10,143. Term of patent 14 years.

To all whom it may concern:

Be it known that I, WILL DEAN ALLEN, a citizen of the United States, and a resident of New Durham, in the county of Strafford and State of New Hampshire, have invented a new, original, and ornamental Design for Handles for Brushes or Similar Implements, of which the following is a specification, reference being had to the accompanying

drawings, forming part hereof, in which the figure is a side view of a handle showing my new design.

I claim:

The ornamental design for a handle for brushes or similar implements as shown in the accompanying drawing.

WILL DEAN ALLEN.
